UNITED STATES PATENT OFFICE.

HENNING PETERSEN, OF THIEF RIVER FALLS, MINNESOTA.

CLAMP OR GRIP.

No. 858,018.

Specification of Letters Patent.

Patented June 25, 1907.

Application filed November 17, 1906. Serial No. 343,946.

To all whom it may concern:

Be it known that I, HENNING PETERSEN, a citizen of the United States, residing at Thief River Falls, in the county of Red Lake and

5 State of Minnesota, have invented a new and useful Clamp or Grip, of which the following is a specification.

This invention relates to means for gripping or clamping wires, cables, and the like.

10 The primary object of the invention is to provide an exceedingly simple article of manufacture that will constitute an effective clamp for guys, wire stretchers, hitching devices and the like, is readily applicable to the 15 article to be clamped, and when in place and strain is applied thereto, will not slip and will not injure the article upon which it is clamped.

The preferred form of construction is illustrated in the accompanying drawings, where-

20 in—
Figure 1 is a longitudinal sectional view through the device showing the same clamped upon a cable; Fig. 2 is a cross-sectional view therethrough on the line 2—2 of Fig. 1; Fig. 3 is a cross-sectional view on the line 3—3 of Fig. 1; Fig. 4 is a side elevation of the structure showing the same applied to a guy cable; Fig. 5 is a top plan view showing the device employed in a stump puller.

30 The same reference numerals are applied to the same parts throughout the several figures of the drawings.

In the embodiment illustrated, straight jaws 6 are employed that are disposed in parallel relation and are in the form of bars having straight longitudinal recessed seats 7 in their opposing inner faces. The ends of these jaws are provided with enlarged rounded ears 8, thereby producing curved ends 40 against which a cable will bear without being cut. The jaws at one end of the device are connected by links 9 located on opposite sides of said ends and secured to the jaws and to each other by rivets or pivot pins 10 passing through the adjacent ears. The jaws at the other end are connected by a yoke, the same consisting of an eye 11 having oppositely extending shoulders 12, from which project parallel integral legs 13. These legs 45 embrace the adjacent ends of the jaws and are secured thereto and to each other by pivot pins or rivets 14 that pass through the adjacent ears 8. If desired, a link 15 may be

located in the eye 11, this eye being disposed in a plane that passes longitudinally through 55 the centers of the jaws and being located at one side of said jaws, as clearly shown.

The device may be employed for a variety of purposes. Thus, in Fig. 4 a guy cable 16 is disclosed, this cable being passed longitudinally through the jaws and about a pulley 17 or other device attached to an anchor 18, the end of the cable being secured to the link 15. With this arrangement, when the links and legs are disposed at right angles to 60 the jaws, the cable is loose between said jaws and the clamp can be moved longitudinally upon said cable, but when strain is applied to the eye, the links are moved to a diagonal position with respect to the jaws, and consequently said jaws are moved toward each other and will clamp firmly upon the cable. Moreover because of the single connection at 65 one end of the device, said device will assume an angular relation with respect to the 70 cable, and the clamping action will thus be all the more secure. Therefore, it is preferable to have the ends of the seats 7 flared in order to avoid all danger of cutting the cable.

As another illustration of the use of the device, attention is invited to Fig. 5, wherein a cable 19 is shown as placed around a stump 20 or other article to be moved. The power for moving the stump is derived from draft animals hitched to the whiffletree 21 and the 75 hook 22 of this whiffletree is engaged in the link 15 of the clamp, said clamp being placed upon the free end of the cable 19. It will be evident that the action of this device, in this 80 instance, is exactly the same as that already 85 described, and it will be evident to those skilled in the art that the clamp can be successfully employed in a variety of ways.

Having thus described my invention, what I claim as new, and desire to secure by Letters Patent, is—

As an article of manufacture, a grip or clamp comprising two straight substantially parallel jaws having straight longitudinal seats in their opposing faces, and enlarged rounded 100 ears at their ends forming rounded ends for a cable to bear against, links applied to the opposite outer sides and pivotally connecting the ears of the jaws at one end, and a yoke comprising an article-engaging eye located 105 at one side of the jaws, and spaced legs inte-

gral with the eye and straddling the opposite outer sides of the jaws at the other end, said legs being pivoted to the ears of both jaws at said end, and said yoke constituting means for applying power at one side of and to the corner of the grip or clamp.

5 In testimony, that I claim the foregoing as

my own, I have hereto affixed my signature in the presence of two witnesses.

HENNING PETERSEN.
